LOADER-BAR, CONTROL TUBE, AND COAL LOADING MACHINE

Myron T. Coffman, Ellamore, W. Va.

Application August 13, 1954, Serial No. 449,753

3 Claims. (Cl. 198—10)

My invention relates to a coal loading machine constructed to work thin seams. It is assumed that the coal to be loaded is cut and/or sheared and shot down and the cuttings removed from the surf cut by the coal cutting machine as in general practice.

One of the objects of my invention is to provide a compact coal loading machine which may be progressively moved beneath a fractured cut of coal for dislodging the aggregate and delivering the aggregate to a conveyor for removal of the coal as fast as the coal accumulates.

Another object of my invention is to provide a construction of loader bar and mechanism for impulsing the bar beneath a fractured cut of coal for delivering the coal to a discharge conveyor.

Another object of my invention is to provide an assembly of chisel-bar, loader bar and conveyor and mechanism for coordinating the operation thereof for the rapid loading of coal in a fractured cut of coal in a coal mine.

Other and further objects of my invention reside in the arrangement of the coal loading mechanism as set forth in the specification hereinafter following by reference to the accompanying drawings, in which:

Fig. 1 is a plan view of the machine of my invention showing the loading boom moved to a position over the conveyor;

Fig. 2 is an elevational view of the machine shown in Fig. 1 looking at the machine from the drive side;

Fig. 3 is a front elevational view of the machine shown in Figs. 1 and 2;

Fig. 4 is an enlarged transverse sectional view taken through the loading section illustrating the loader bar which contains a multiplicity of longitudinally extending steps therein associated with a counterweight and the means operated through the center of gravity of the counterweight for biasing the bar to move it to a vertical upward position and the means for moving the bar downwardly intermediate the upward movement thereof, the view showing the loader bar moved to its lowermost position;

Fig. 5 is a view similar to the view illustrated in Fig. 4 but showing the loader bar moved to its extreme upward position;

Fig. 6 is a horizontal sectional view through the loader bar of Figs. 4 and 5, the view being taken substantially on line 6—6 of Fig. 4 and wherein the cranks for moving the bar downwardly have been shown in the horizontal positions thereof in order to clarify the disclosure;

Fig. 7 is a fragmentary vertical sectional view taken on line 7—7 of Fig. 6;

Fig. 8 is a fragmentary enlarged elevational view illustrating the drive means for operating the loader bar;

Fig. 9 is a transverse sectional view taken through a modified form of my invention illustrating a longitudinally extending crank passing through a slot located at the center of gravity of the counterweight, the crank being rotatably driven for imparting movement in a vertical direction to the counterweight and loader bar; the view il-

lustrating the counterweight loader bar in its lowermost position;

Fig. 10 is a view similar to the view illustrated in Fig. 9 but showing the counterweight and loader bar moved to its extreme upward position;

Fig. 11 is a view similar to the views shown in Figs. 9 and 10 but illustrating the longitudinally extending crank moved in its orbit to the extreme left within the slot through the center of gravity of the counterweight; the view illustrating the fact that the movement of the counterweight and the loader bar is restricted to a vertical plane and having no movement in a lateral direction;

Fig. 12 is a fragmentary view similar to the views illustrated in Figs. 9—11 but illustrating the longitudinally extending crank moved in its orbit to the extreme right while maintaining the movement of the counterweight and loader bar wholly in a vertical direction;

Fig. 13 is a horizontal sectional view taken through the counterweight and longitudinally extending crank for driving the counterweight of the form of my invention shown in Figs. 9—11, the view being partially broken away and shown in longitudinal section;

Fig. 14 is an elevational view of the drive means for the longitudinally extending crank shown in the form of my invention illustrated in Figs. 9—13;

Fig. 15 is a side elevational view of the loading boom employed on the coal loading machine of my invention, the view being broken away and illustrated in section to show the double-thread bar and the manner of driving the ploughshare for moving the coal onto the conveyor;

Fig. 16 is a vertical sectional view taken on line 16—16 looking at the end of the loading boom;

Fig. 17 is a fragmentary vertical sectional view taken on line 17—17 of Fig. 15;

Fig. 18 is a vertical sectional view taken on line 18—18 of Fig. 15;

Fig. 19 is a vertical sectional view taken on line 19—19 of Fig. 15; and

Fig. 20 is a diagrammatic view showing two of the machines of my invention operating at a working face of coal.

The machine invented, is of steel alloy and consists of a loader-bar in two sections, operated individually in unison (Figure 1—1) in the shape of an inverted L a cross-section of which (Figure 4) is a triangle with the height approximately one-half the width of base, with an inclined succession of steps with vertical risers of one inch (in this case to illustrate) from bottom to top on the hypotenuse. The number of steps varying with the height the load is to be raised. In the open side of the inverted L is a conveyor of conventional design, which extends approximately five feet past the open end of the inverted L. Immediately at the open end of the loader-bar and fastened to the side of the conveyor is encased machinery 8, consisting of motive power, clutches, wire cable reels for locomotion, hydraulic pump, etc. (Figures 1—2—3—5—8).

The length of the loader-bar is seven feet from the machine case. Over and above the leading edge of the loading-bar, a double-thread-bar extends. It carries a follower from which an arm extends and on which, is fastened a "ploughshare" 5. This double-thread-bar (Figs. 15—19) is in a tube which has two open slots on opposite sides, the length of the threads. The lower lip of slot opening supports and guides the ploughshare in its traveling back and forth. The pipe aforementioned, is attached to the machinery case and pivots from that point, and on top of the pipe at the far end, is a double-action hydraulic cylinder from which a chisel-bar works.

The tube or pipe, with mentioned parts in and on it, can be moved horizontally, in an arc, from the leading edge of the loader-bar, to the far right hand corner of

the forward edge of the loading-bar, and the plowshare can be moved in a vertical arc, so the blade or plowshare will run along close to the leading edge of the loader-bar, farther up in the material to be loaded or close to the top of same. All of which is to disturb and dislodge the aggregate or coal, to fall or slide to, or on the bar, which is at the same time, moving up and down one inch—in this case—at 360 times per minute. And all of the above-mentioned machinery is movable horizontally, by means of jackpipes and blocks and wire rope, as a conventional coal cutting machine does.

The entire machine is on a sheet metal base, with wedge-shaped 2 leading edge in front of loader-bar (Figure 1). The loader-bar rubs against turned-up edges of the base.

The machine moves under the pile of material by continually working its way under the aggregate, raising the material up and over the top step and discharging it on the conveyor, which moves it forward, discharging into a conveyor. (Figure 20.)

The face of the material to be loaded, has a tendency to slide or fall, either concavely or convexly, when disturbed. And the continually controlled moving of the plowshare, the hydraulic chisel and the continual up and down movement of the loader-bar, as they conjointly move horizontally on the pavement or floor, under the material, coact to perform the loading operation.

Further versatility and adaptability of the invented loader bar can be described by representing that should the pavement or floor on which the coal lies, tilt down forward, the forward end of the loader-bar can be swung ahead by tightening the tail-rope of the machine; the material then tending to come forward as well as up and over the loading-bar. If the floor tilts up, the loader-bar is swung the other way by regulating the tail-rope. This adjustment can be made to the diminishing point. Should the coal become excessively heavy in height, horizontal movement is stopped and the top coal disturbed with blade arm 5 causing it to fall over the top of the bar whereupon the arm can resume horizontal movement.

One advantage of the loading machine of my invention is its comparatively short length—the same as the average cutting machine—which enables safety posts to be carried close to the coal face, as required by law.

Part marked 1 on all sections consists of a stepped loading section which moves vertically to raise the coal over the side of the conveyor 7. The movement comes from a cam shaft with the drive in housing 8.

Part marked 2 has a triangular metal cutting edge, all around, and forms a part of the base plate 3 in the loading area.

Part marked 3 is a continuous base plate under the entire machine. The machine is pulled over the floor on this plate by means of wire rope drums 33 and 34 mounted on housing 8.

Part marked 4 is a double thread bar (Figs. 15-18).

Part marked 5 is a disturber shaped as a plowshare and traveling along the double thread bar 4 as well as around it and whose function is to push coal toward the vibrating stepped loading section 1.

Part marked 6 is a chisel-bar to assist in disturbing material.

Part marked 7 is a conveyor of standard construction.

Part marked 8 is the housing for the conveyor (7) drive, boom 4, ploughshare 5 and drill (6) drive and the wire rope drums 33 and 34 for the machine travel.

Part marked 9 is an apron to evenly distribute load across conveyor 7.

Referring to Figs. 15-19:

Part marked 10 is a tube or slotted housing.

Part marked 11 is a double thread bar, on which the follower nut 12 runs to which is attached arm 5 which holds the blade or plowshare.

Part marked 13 is a rack around and attached to part 10 turned by pinion wheel 16.

Parts 14 are thrust collars fastened to tube 10.

Part 15 is an eye in which tube 10 is supported and in which it is manually turned by wheel 16 through rack 13.

5 Bar 11 extends to end of tube 10 and is driven by the hydraulic impeller to which a hydraulic rubber hose feeds. Bar 11 is approximately 2" in diameter.

In the form of my invention illustrated in Figs. 4-8 the counterweight 17 which is secured to the underface of the stepped section 1 of the loader bar includes steps in the upper surface thereof which are contiguous with at least two of the steps in the loader bar. Coil springs 18 bias the counterweight 17 to move to a vertical upward position. The counterweight 17 is recessed or slotted

10 at one side in the positions indicated at 19 for receiving the ends of the cranks 20 which have sleeves 24 thereon fitting within the slots 19. The cranks 20 have worm gears 21 mounted on the ends thereof; the gears are driven by the worms 22 carried by drive shaft 22a driven by

15 motor 23 mounted in the housing 8. The arrangement of slots 19 is such that cranks 20 with the bearing sleeves 24 located thereon move the counterweight 17 only in a vertical plane while the cranks may be displaced within the slots 19 so that there is no longitudinal movement of

20 counterweight 17, as shown more clearly in the fragmentary elevational view of Fig. 7.

In the form of my invention shown in Figs. 9-14 the counterweight is illustrated at 25 disposed beneath the stepped loader bar 21 and having a longitudinally extending

30 slot 26 therein disposed along the center of gravity of the counterweight. Coil springs 18 bias the counterweight vertically upwardly. A longitudinally extending crank 27 having bearing sleeve 29 thereon extends longitudinally through the slot 26 and is driven from the end

35 28 thereof through worm gear 30 operated by worm 31 driven by motor 23 located within housing 8. Crank 27 in operating in its orbit moves counterweight 25 downwardly against the bias action of coil springs 18 while the stepped loader bar is urged upwardly by the tension

40 exerted by coil springs 18. By reason of the extended slot 26 the crank 27 controls the movement of the counterweight only in a vertical plane (Figs. 9 and 10) and there is no movement of the counterweight or loader bar trans-

versely as illustrated in Figs. 11 and 12.

45 While I have described my invention in certain of its preferred embodiments I realize that modifications may be made and I desire that it be understood that no limitations upon my invention are intended other than may be imposed by the scope of the appended claims.

What I claim as new and desire to secure by Letters 50 Patent of the United States is:

1. A coal loader comprising a movable base, a longitudinally extending loader-bar mounted on said base, said loader-bar having a multiplicity of longitudinally extending

55 steps therein, means for biasing said bar to move to a vertically upward position, and means for moving said bar downwardly intermediate the vertically upward movement thereof in which said means for moving said bar downwardly intermediate the vertically upward movement thereof includes a counterweight attached to the inner

60 surface of the top of said loader-bar.

2. A coal loader comprising a movable base, a longitudinally extending loader-bar mounted on said base, said loader-bar having a multiplicity of longitudinally extending

65 steps therein, means for biasing said bar to move to a vertically upward position, and means for moving said bar downwardly intermediate the vertically upward movement thereof in which said means for moving said bar downwardly includes a counterweight beneath said bar

70 and driving means extending through said counterweight for imparting movement thereto in a substantially vertical direction.

3. A coal loader comprising a movable base, a longitudinally extending loader-bar mounted on said base, said

75 loader-bar having a multiplicity of longitudinally extend-

ing steps therein, means for biasing said bar to move to a vertically upward position, and means for moving said bar downwardly intermediate the vertically upward movement thereof in which said means for moving said bar downwardly includes a counterweight beneath said bar and driving means extending through said counterweight for imparting movement thereto in a substantially vertical direction, said counterweight including steps in the upper

surface thereof which are contiguous with at least two of the steps in said loader-bar.
